UNITED STATES PATENT OFFICE.

AARON T. CARROLL, OF SCRANTON, PENNSYLVANIA, ASSIGNOR OF ONE-HALF TO
THOMAS F. FOLEY, OF SCRANTON, PENNSYLVANIA.

ADJUSTABLE TOE-CAP.

1,317,427.

Specification of Letters Patent. Patented Sept. 30, 1919.

Application filed July 19, 1918. Serial No. 245,640.

To all whom it may concern:

Be it known that I, AARON T. CARROLL, a citizen of the United States, residing at Scranton, in the county of Lackawanna and State of Pennsylvania, have invented certain new and useful Improvements in Adjustable Toe-Caps, of which the following is a specification.

This invention relates to toe caps for boots and shoes and has for its object to provide a comparatively simple and inexpensive device of this character capable of being readily attached to a boot or shoe, either during the manufacture thereof or after the shoe is made, and which will effectually protect the toe of the shoe and the adjacent tip of the sole against excessive wear and abrasion.

A further object of the invention is to provide a toe cap or protector stamped or otherwise formed from a single sheet of metal and so constructed as to fit the toes of shoes of different sizes.

A further object is to provide the cap or protector with an inwardly extending flange which fits between the toe portion and sole of the shoe and serves to center the cap in position on the shoe and also to reinforce and strengthen said cap.

A further object is to provide a toe protector including a segmental cap piece having a depending flange and provided with an inwardly extending plate for attachment to the sole of a shoe, said attaching plate being formed with clefts or incisions to permit shaping of the protector to the toe and sole of the shoe.

A still further object of the invention is generally to improve this class of devices so as to increase their utility, durability and efficiency.

Other and incidental objects will appear as the description proceeds. In the drawings wherein I have illustrated the preferred embodiment of the invention, and wherein similar reference characters designate corresponding parts throughout the several views:

Figure 1 is a perspective view of a portion of a shoe showing my improved adjustable toe cap in position thereon;

Fig. 2 is a transverse sectional view taken on the line 2—2 of Fig. 1 and looking in the direction of the arrows;

Fig. 3 is a perspective view of the toe cap or protector detached.

Corresponding and like parts are referred to in the following description and indicated in all the views of the drawings by the same reference characters.

The improved toe cap forming the subject-matter of the present invention is preferably stamped or otherwise formed from a single sheet of metal and comprises a cap piece 5 curved to conform to and adapted to fit over the toe of a shoe, indicated at 6, and having its upper longitudinal edge inclined downwardly in opposite directions, as indicated at 7. The material of which the cap 5 is formed is pressed or forced inwardly to form a laterally extending flange 8 adapted to be positioned between the toe 6 of the shoe and the sole 9, as best shown in Fig. 2 of the drawings, said flange serving to center the cap on the toe of the shoe and also serving to reinforce and strengthen said cap. Depending from the flange 8 is a marginal flange 10 which fits over the outer edge of the sole 9 at the toe portion of the shoe, there being openings 11 formed in the flange 8 at predetermined intervals for the reception of nails or similar fastening devices 12 by means of which the cap or protector is retained in position on the toe of the shoe. The flange 8 conforms to the shape of the cap and preferably extends throughout the entire inner circumference thereof, while the depending flange 10 is coextensive with the outer circumferential wall of the cap and covers the major portion of the sole 9 at the toe of the shoe, as best shown in Fig. 1 of the drawings. By making the toe cap or protector in this manner the outer ends of the cap may be pressed together or spread apart so as to adapt the cap to the toes of shoes of different sizes.

The flange 8 is preferably formed with one or more V-shaped incisions 8' so as to permit the flange and cap to be bent or expanded and contracted to fit the toes of shoes of different sizes.

The metal, after depending flange 10 is formed, is preferably pressed inwardly to provide oppositely disposed segmental attaching flanges 12' and a centrally disposed attaching plate 15 adapted to bear against the tread face of the sole and form a protection thereto in the act of walking. The

attaching plate 15 and the segmental flanges 12' are provided with openings 14 for the reception of nails or other fastening devices which latter are adapted to be driven into the sole 9 and assist in retaining the protector in position on the shoe. The inner edge of the attaching plate is preferably straight and provided with V-shaped clefts or incisions 16, there being similar clefts or incisions 17 formed in the attaching flanges 12' so as to permit ready expansion and contraction of the toe protector to fit shoes of different sizes.

It will thus be seen that the segmental cap 5 forms an efficient protection for the toe of the shoe, while the depending flange 10 protects the lip of the sole 9 thereby preventing excessive wear on or abrasion of said parts of the shoe. It will also be noted that inasmuch as the attaching plate 15 bears against the tread face of the sole it follows that said plate not only forms an additional means for attaching the protector to the shoe but also provides an additional wearing surface for the sole of the shoe at the point subjected to the most wear. It will, of course, be understood that the

toe caps or protectors may be made in different sizes and shapes to conform to the different styles or grades of boots and shoes 30 and that said cap protectors may be nickelated, japanned or otherwise plated or coated so as to protect the same from the deleterious actions of the elements. The device being stamped from a single sheet of metal, may 35 be conveniently manufactured and placed upon the market at a minimum price so as to be within the reach of all.

Having thus described my invention, what is claimed as new is:

An adjustable toe protector for boots and shoes comprising a cap having an inwardly extending flange and a depending flange terminating in an inwardly extending attaching plate, there being segmental flanges, disposed on opposite sides of the attaching plate and substantially V-shaped incisions formed in the inner edges of the inwardly extending flange, segmental flanges and said attaching plate to permit expansion and 50 contraction of the cap.

In testimony whereof I affix my signature.

AARON T. CARROLL. [L. S.]
